UNITED STATES PATENT OFFICE.

CHARLES T. WESTLAKE, OF ST. LOUIS, MISSOURI, ASSIGNOR TO FLORY CARRY IRON COMPANY, OF ST. LOUIS, MISSOURI, A CORPORATION OF DELAWARE.

DRAW-BAR CARRY-IRON.

1,125,420.

Specification of Letters Patent.

Patented Jan. 19, 1915.

Application filed August 5, 1912. Serial No. 713,307.

To all whom it may concern:

Be it known that I, CHARLES T. WESTLAKE, a citizen of the United States, residing at St. Louis, Missouri, have invented a certain new and useful Improvement in Draw-Bar Carry-Irons, of which the following is a full, clear, and exact description, such as will enable others skilled in the art to which it appertains to make and use the same, reference being had to the accompanying drawings, forming part of this specification, in which—

Figure 1 is a front elevational view of a carry iron of my improved construction with the draw-bar that is supported by said carry iron in section. Fig. 2 is an enlarged vertical section taken on the line 2—2 of Fig. 1. Fig. 3 is a section similar to Fig. 2 and showing the roller carry iron reversed or turned up-side-down relative to the position shown in Fig. 2 so as to elevate the draw-bar. Fig. 4 is a perspective view of the carry iron.

My invention relates to new and useful improvements in draw-bar carry irons, the principal objects of my invention being, to provide a simple carry iron in the form of a roller, the end portions of which rest upon suitable supports depending from the striking plate or dead block that is applied to the end portion of the car underframe, and which carry iron has free rolling movement longitudinally of the car for a limited distance, thereby providing a roller bearing for the supported draw-bar, and further to form the central portion of the carry iron eccentric relative to its end portions so that when the carry iron is reversed or turned up-side-down the supported draw-bar is elevated, thereby making said draw-bar adjustable in height.

By making the carry iron in the form of a roller and permitting the same to move lengthwise of the car, the friction between the supported draw-bar and carry iron is reduced to a minimum, and said draw-bar thereby moves freely under the draft and buffing strains imparted thereto.

With the above objects in view, my invention consists in certain novel features of construction and arrangement of parts hereinafter more fully described and claimed.

Referring by numerals to the accompany-

ing drawings, 1 designates the end sill of a car underframe, 2 a striking plate or dead block, and depending from the ends thereof are suitable brackets 3. Formed integral with or fixed to the lower ends of these brackets 3 are inwardly projecting flanges or ledges 4 which serve as supports for the end portions of the roller carry iron. This carry iron shown in Fig. 4 comprises a main body portion 5 that is substantially cylindrical in form, and formed on or fixed to the end portions of said body and eccentrically disposed with respect to the axis thereof, are circular lugs or trunnions 6 which rest directly upon the flanges or ledges 4 when the carry iron is properly positioned for use. Formed through the carry iron thus constructed is a longitudinally extending opening 7 that is substantially oval in cross section, and passing through this opening is a pin or bolt 8, the end portions of which are removably seated in the lower portions of the bracket 3. The opening 7 is centrally disposed in the eccentrically arranged lugs or trunnions 6, and thus that portion of the opening through the body 5 is located to one side of the axis of said body, which arrangement provides bearing surfaces on opposite sides of the body 5 that are located at different distances away from the axis of the opening.

The bearing surface located nearest the axis of the opening may be termed the low bearing surface and is designated by 5^a, while the opposite or high bearing surface is designated by 5^b. When in use the lugs or trunnions 6 on the ends of the carry iron are positioned on the flanges or ledges 4 with the pin or bolt 8 extending through the opening 7, and the draw-bar A rests directly on top of the body 5, as shown in Fig. 1. As the draw-bar moves lengthwise under the influence of draft and buffing strains the lugs or trunnions 6 ride forward and backward upon the flanges 4, and the roller support thus formed reduces the friction between the draw-bar and the carry iron to a minimum. The opening 7 is centrally arranged relative to the axis of the trunnions 6, and as these trunnions are eccentrically arranged on the ends of the roller 5, said opening 7 is necessarily off center with respect to the axis of the body 5.

the roller 5. The greatest width or major axis of the opening 7 is substantially at right angles to a plane through the axes of the roller and its trunnion, and thus when 5 the carry iron is positioned so as to support the draw-bar in either high or low position the opening 7 occupies substantially a horizontal plane. The width of the opening 7 is approximately twice the width of the pin 10 or bolt 8, and as the roller moves longitudinally under the influence of the supported draw-bar, the pin or bolt performs the function of a stop to limit both the backward and forward movements of the roller. The 15 length of the backward and forward movement of the roller with relation to the bearing surfaces 5^a and 5^b is such that there is no appreciable vertical movement of the draw-bar during the backward and forward 20 rolling movement of the carry iron.

To adjust the height at which the draw-bar is carried the roller is reversed or turned up-side-down, which action can be readily accomplished by removing the pin 25 or bolt 8. When it is desired to support the draw-bar in a comparatively low plane the carry iron is positioned so that said draw-bar engages upon the low bearing surface 5^a, as shown in Figs. 1 and 2, and when it 30 is desired to support the draw-bar in a comparatively high position the carry iron 5 is turned up-side-down so that the draw-bar engages on the high bearing surface 5^b, as shown in Fig. 3.

35 A carry iron of my improved construction is very simple, can be easily and cheaply manufactured, can be readily positioned for use or removed therefrom, and being in the form of a roller, provides an ideal support 40 for a draw-bar for the reason that friction between the draw-bar and support is reduced to a minimum, and the roller support readily yields longitudinally of the car to the movements of the draw-bar while 45 the same is in service.

It will be readily understood that minor 50 changes in the size, form and construction of the various parts of my carry iron can be made and substituted for those herein shown 55 and described without departing from the spirit of my invention, the scope of which is set forth in the appended claims.

I claim:

1. In a carry iron, a roller having draw 55 bar bearing faces arranged at different distances from the axis of the roller, which roller is supported so as to roll lengthwise of the car body under the influence of the supported draw bar.

2. A draw bar carry iron, comprising a roller, eccentrically arranged trunnions on the ends thereof, and bearings upon which the trunnions are mounted for backward and forward rolling movement.

3. The combination with a pair of spaced

supports arranged transversely with respect to the longitudinal axis of the car body, of a draw bar carry iron having a plurality of draw bar bearing faces located at different distances from its axis, and the end portions 70 of which carry iron are mounted for rolling movement longitudinally with respect to the car body on said supports.

4. The combination with supports, of a draw bar carry iron, and eccentrically arranged trunnions on the ends thereof, which trunnions are mounted for rolling movement 75 on the supports.

5. The combination with supports, of a roller, the ends of which are mounted for 80 rolling movement on the supports, and means seated in the supports and passing through the roller for limiting the rolling movement of said roller relative to said supports.

6. The combination with supports, of a roller carry iron having its ends mounted for rolling movement on the supports, and means seated in the supports and engaging the roller for limiting the rolling movement 90 thereof.

7. The combination with supports, of a carry iron comprising a cylindrical body, eccentrically disposed trunnions on the ends of said body, which trunnions are adapted 95 to roll backward and forward upon the supports, and means passing through the carry iron for limiting its rolling movement.

8. In a device of the class described, a roller, eccentrically disposed trunnions on the 100 ends thereof, and there being an opening formed through said roller and trunnions, which opening is axially arranged with respect to the trunnions and eccentrically arranged with respect to the roller.

9. In a device of the class described, a carry iron comprising a roller, eccentrically disposed trunnions on the ends of said roller, and there being an opening through said 105 roller and trunnions, which opening is substantially oval in cross section.

10. A draw bar carry iron comprising a roller having a cylindrical body, trunnions on the ends thereof, a portion of the surface of which body is eccentric with respect to the axis of the trunnions, and supports upon 110 which the trunnions are adapted to roll.

11. A draw bar carry iron comprising a cylindrical body portion, trunnions on the ends thereof, a portion of the surface of which cylindrical body is eccentric with respect to the axis of the trunnions, bearings on which the trunnions are mounted for rolling movement, and means on said bearings for limiting the movement of the trunnions.

12. A draw bar carry iron comprising a roller, trunnions on the ends thereof, and there being an opening through said roller and its trunnions, which opening is sub- 130

stantially oval in cross section and eccentrically arranged with respect to the axis of the roller.

13. The combination with a draw bar, of 5 a roller transversely disposed beneath said draw bar and supporting the same, which roller is adapted to roll longitudinally with respect to the car under the influence of the lengthwise movement of the draw bar, and 10 means passing through said roller for limiting its rolling movement.

14. The combination with supports arranged at the sides of a draw bar opening, which supports are provided with horizontally disposed flat bearing surfaces, of a draw bar supporting roller arranged between said supports with its ends bearing upon the flat surfaces thereof, which roller is adapted to roll lengthwise of the car body 20 under the influence of the supported draw

bar, and means seated in the supports and engaging the roller for limiting its rolling movement.

15. The combination with supports, of a cylindrical carry iron, the ends of which 25 bear upon said supports, there being an opening lengthwise through said carry iron, and a retaining member seated in said supports and passing through the opening in the carry iron, which opening is of sufficient 30 size to permit the carry iron to bodily roll freely in both directions.

In testimony whereof I hereunto affix my signature in the presence of two witnesses, this 31st day of July, 1912.

CHARLES T. WESTLAKE.
